UNITED STATES PATENT OFFICE.

SIDNEY H. CLUXTON, OF WASHINGTON, DISTRICT OF COLUMBIA.

DEVICE FOR AUTOMATICALLY STOPPING VEHICLES.

No. 923,020.

Specification of Letters Patent.

Patented May 25, 1909.

Application filed January 5, 1907. Serial No. 351,003.

To all whom it may concern:

Be it known that I, SIDNEY H. CLUXTON, a citizen of the United States, residing at Washington, in the District of Columbia, have invented certain new and useful Improvements in Devices for Automatically Stopping Moving Vehicles; and I do hereby declare the following to be a full, clear, and exact description of the invention, such as will enable others skilled in the art to which it appertains to make and use the same.

My invention relates to new and useful improvements in devices for stopping moving vehicles and is adapted more particularly for use in connection with railway tracks for stopping trains and my object is to provide electro-magnets and dispose the same below a portion of the rails of the track way and connect the same with any suitable form of electric current so that when said magnets are energized the rails connected thereto will be magnetized and the speed of the train checked.

A further object is to provide suitable means upon parts of the railway coaches which is adapted to be attracted to the magnetized rail and form a brake.

A still further object is to provide a suitable connection between the depending portion and the usual form of air brakes whereby when the depending portion is attracted the air brakes will be operated.

Other objects and advantages will be hereinafter referred to and more particularly pointed out in the claims.

In the accompanying drawings which are made a part of this application, Figure 1 is a perspective view of a portion of a track way showing the usual form of block system in connection therewith and my improved device applied thereto. Fig. 2 is a side elevation of a portion of the track way and a car truck thereon and showing my improved devices secured thereto. Fig. 3 is a detail plan view of a portion of a track way showing a plurality of electro-magnets mounted in position thereunder and, Fig. 4 is a side elevation of a depending shoe and means secured thereto to operate the air brakes when the shoe is attracted.

Referring to the drawings in which similar reference numerals designate corresponding parts throughout the several views, 1 indicates a track way and 2 a switch in connection therewith, said track way and switch being constructed in the usual or any pre-

ferred manner and such as are commonly used to transport railway trains.

Located at any suitable point at one side of the track way 1 is the usual form of signal tower 3 which is employed in connection with the well known block system for despatching trains. In systems of this class it is customary to display at any convenient point certain colored semaphores or signals 4, which are used for indicating to the engineer of an approaching train the condition of the track between the next succeeding blocks. If a train is occupying the next succeeding block the danger signal is set at the tower at the beginning of the block so that a train approaching the block will be stopped until the next succeeding block is cleared and in order to positively prevent the train from entering the block or ignoring the danger signals until such time as the block is clear I provide any number of electro-magnets 5 which are adapted to be located below a specified section of the track rails 6 and at any suitable distance from the tower, said electro-magnets being connected in the usual or any preferred manner by wires 7 while each battery of magnets is connected to any suitable source of electric supply through line wires 8, said wires extending through the tower and are operatively connected to feed wires 9.

At a point within the tower, the line wires 8 are provided with the usual form of contact points 10 which are adapted to be closed or opened through the medium of the signal levers 11 so that when the semaphores, which are operated by said levers, are set as a danger signal, the signal levers 11 will engage the contact points and complete the circuit through the line wires 8 and electro-magnets 5 thereby energizing said magnets and magnetizing the track rails to which the magnets are secured so that as soon as the train encounters the magnetized rails, the speed of the train will be checked.

In order to positively stop the train through the medium of the magnetized rails I secure at any suitable point upon the train and preferably the truck 12, a depending metallic shoe 13 which may be of any preferred construction and length and secured to the car in any preferred way and in this instance the shoe is provided with vertically extending standards 14 which are directed through suitable bearings 15 on the trucks 12 so that said shoe may be raised or lowered

when desired and in order to normally hold said shoe out of engagement with the track rails 6 I provide the upper ends of the standards 14 with heads 16 and dispose around 5 the standards 14 between the heads 16 and the bearings 15, tension springs 17, said springs being employed to raise the metallic shoe 13 when released from the rail and hold the same normally out of engagement with 10 the track rails. As soon, however, as the trucks move on to the magnetized portion of the rails, the shoes 13 will be attracted and drawn into engagement with the upper surface of the track rails and it will be 15 seen that by sufficiently magnetizing the track rails the metallic shoe will be held with sufficient firmness against the rail as to rapidly check the speed of the train and as soon as a sufficient number of metallic shoes 20 have been directed into engagement with the magnetized portion of the rail the train will be completely stopped where the same will be held as long as the electric current is 25 passing through the electro-magnets. As soon, however, as the block is cleared, the 30 danger signal is lowered which will result in breaking the circuit through the line wires 8 and removing electric energy from the magnets 5 so that the metallic shoes 13 will be released whereupon the springs 17 will elevate said shoes a predetermined distance above the track rail when the train 35 may again proceed on its journey.

It is also customary to open and close 35 switches from the tower and it will be understood that by providing suitable contact points for the movable portions of the switch rails the electro-magnets 5 can be energized when either end of the switch is 40 opened so that it will be impossible for a train approaching the switch from entering 45 the same and becoming wrecked, it being understood, of course, that the electro-magnets are to be placed a sufficient distance from the ends of the switch to allow a train 50 to stand upon the track way between the battery of electro-magnets and the ends of the switch so that the same may move freely upon the switch if so desired.

55 In order to confine the electric current to certain portions of the track rails, said magnetized rails are insulated from the remainder of the track way by any suitable form of insulation 18 which is disposed between the meeting ends of the rails and around the fish plates connecting the same.

60 Any number of electro-magnets may be employed and distributed under any number of the track rails and in order to simultaneously magnetize all of the track rails engaged by the magnets, the meeting ends of the magnetized rails are electrically connected together in any preferred manner as best shown at 19 in Fig. 3.

65 As a further means for stopping the train

when the same is inclined to pass the danger signals, I have provided means for operating the air brakes upon the train through the action of the shoe 13 and in this connection I dispose at any suitable point in the 70 air pipe 20, a cock 21 which is provided with an operating lever 22 to the free end of which is secured a link 23, said link being in turn pivotally secured to one end of a rocking beam 24 while to the opposite end of said beam is pivotally secured a rod 25, the lower end of which is secured in any preferred manner to the shoe 13 so that when said shoe is attracted to the rail the beam 24 will be rocked and the cock 21 rotated which will 80 result in operating the air brakes which in connection with the metallic shoe will quickly stop the train.

75 I am aware that it is not new to direct a shoe into engagement with the track to stop the train and I am also aware that it is not new to employ an electric current for setting the brakes upon the train, but my invention consists in disposing electro-magnets below the track rails and connecting the 85 same with an electric current so that when said magnets are energized certain of the track rails will be magnetized and said magnetism employed to attract a depending shoe and hold the same into engagement with the 90 upper surface of the track rails and in this connection it will also be seen that a certain degree of attraction will be directed through the car wheels and thus aid in checking the 95 speed of the train.

100 It will now be seen that I have provided means for positively stopping a train when the danger signal is set or when the switch is open and it will also be seen that I have provided a device which may be quickly installed and at a minimum cost.

105 What I claim is:

110 1. The herein described means for stopping vehicles comprising the combination with supporting rails for said vehicles; of electro-magnets secured to said rails, depending shoes on said vehicles and over the rails and means to energize said magnets whereby the rails will be magnetized and the 115 shoes attracted to and held thereon to check the speed of the vehicle.

120 2. The herein described means for stopping vehicles comprising the combination with supporting rails for the vehicles; of electro-magnets secured to said rails, shoes on said vehicle, means to energize said magnets whereby the rails will be magnetized and the shoes attracted thereto, air pipes on said vehicles and means disposed between said air brake mechanism on said vehicle and shoes to operate the same when the shoe is attracted.

125 3. The herein described means for stopping vehicles comprising a battery of electro-magnets, means to energize said magnets and 130

means to form an elongated terminal for said battery whereby depending portions of the vehicle will be attracted and held in its attracted position while traveling the full length of the battery of magnets.

4. The herein described means for stopping vehicles comprising a battery of electro-magnets, means to energize said magnets, and an elongated terminal for said battery of magnets whereby when the same is magnetized portions of the vehicle will be attracted and held in frictional contact therewith throughout its length.

5. The herein described means for stopping vehicles comprising an elongated magnet, means to energize said magnet whereby parts of the vehicle will be attracted and held into frictional engagement with said magnet until the vehicle is stopped.

In testimony whereof I have signed my name to this specification in the presence of two subscribing witnesses.

SIDNEY H. CLUXTON.
